DEFLECTOR FOR VERTICAL MIXING MACHINES

Walter F. Dehuff, Glen Rock, Pa., assignor to
American Machine & Foundry Company, a corporation of New Jersey

Application December 10, 1937, Serial No. 179,036

2 Claims. (Cl. 259—1)

This invention relates to a mixing machine, especially to a mixer of the vertical type, and is more particularly useful when embodied in such a machine in which foam batches are whipped up from liquid or semi-liquid materials, although my invention is intended to be used in any field for which it is adapted by the nature of the improvements herein disclosed.

In whipping up foam batches in vertical mixers, a difficulty in operation arises from the liquid or semi-liquid character of the ingredients, which causes them to collect at a point remote from the beater, owing to the beater-induced centrifugal force which causes a swirling action of the material around the inside of the bowl, making it rather difficult for the beater or whip operating upon this material to collect it and to change the material from its liquid state to the desired foamy structure.

The above-described condition is more apparent in proportion as the diameter of the bowl is increased, and it follows naturally that the over-all time required to convert the liquid or semi-liquid material into the desired condition of foam increases to a point where two very undesirable results have arisen: viz.,

First, the length of time consumed is commercially objectionable;

Second, and by far the more important, the construction of the foam, in the end product, when the batch should be finished, according to accepted practice, is not as uniform as it should be, owing to the fact that the first foam created by the beater or whipper has been whipped too long in order to build up all of the liquid or semi-liquid into a proper foam construction.

Such undesired results have proved detrimental to the finished product, from the standpoint of economical commercial production, as they have caused one portion of the batch to be over-worked, until the last portion of the batch should be properly worked.

After extended research and experimentation with variously modified forms of beaters and whippers, in the effort to trap this swirling liquid, it was decided not to pursue further such an unfruitful course of procedure, and the present applicant conceived the idea of providing a "deflector" device, comprising, in its now-preferred form, a light element which can be readily slipped onto the edge of the bowl, and removed therefrom, and which, when in operative position, will protrude into a position designed to cause the material, as it swirls, to be deflected from a fixed path into the path of the beater.

This improved deflector element is found, in practice, to deflect the revolving liquids in such a manner that the foam structure is built up uniformly throughout the complete mixing operation, and its use has materially lessened the time required to secure uniform construction of foam.

The advantages of the invention will be set forth more at length in the description of the accompanying drawing, in which like characters of reference have been applied to similar parts in the several views which make up the drawing, in which:

Fig. 1 is a sectional elevation, taken on the line 1—1 of Fig. 2, of a mixing machine of the vertical type, showing how the deflector is assembled with the bowl;

Fig. 2 is a plan view of the structure shown in Fig. 1; and

Fig. 3 is a detail view, in rear elevation, of a deflector element in the construction of which the present invention has been embodied, the same being shown separately.

In a now-preferred embodiment of the invention, selected for illustration and description, the deflector element is designated generally by the reference character D, and is shown in combination with a bowl 12, supported in a base 14 of known type, in a vertical mixing machine of the general type of which an example is illustrated and described in the application of De Huff for United States Letters Patent, Serial No. 73,853, filed April 11, 1936.

The vertical mixer as herein illustrated, in Fig. 1, includes a complete head 15 which carries a beater or whipping device 13, and owing to the fact that as the beater 13 rotates about its own axis it is also revolved, in the direction of the arrow in Fig. 2, about the general axis of the beater, which coincides with the center of the circle also bearing an arrow in Fig. 2, it follows naturally that inasmuch as the beater rotates at the rate of approximately four turns for every revolution of the beater bodily around the aforesaid axis of the beater head, the material being mixed takes up the direction outlined by the series of arrows in Fig. 2.

The tendency to swirling action is caused by the above two motions, constituting a planetary motion of the blade 13 around the sun motion of the head.

To counteract the aforesaid swirling action, in pursuance of the invention, provision is made of a deflector element D, which is shown in its operative position in full lines at 10 in Fig. 1, while the beater 13 is shown, in full lines, in its

nearest proximity to the deflector D, and by dot-and-dash lines in its most remote position from said deflector D.

The deflector, in the form illustrated, consists of a unitary structure stamped up from sheet metal, being formed with an operating part 16 which comprises diverging wings having medial notches 17 at their spaced medial rear margins, and an attachment part 18 which includes a web 19 spanning the upper portion of the space between said wings, and having a rearwardly offset upper portion 21, bent downwardly in the form of a handle 19, ending in a spring tongue adapted to be engaged at its tip 22 with the outer wall of the bowl, co-operating with said web 19 to embrace said wall retentively at a region remote from the rim 23 of the bowl, while said offset portion 21 rests upon said rim, thus limiting the downward projection of the deflector into the bowl, so that it will extend properly through the upper surface of the mix, and into the space between the orbit of the beater 13 and the inner wall 12 of the bowl.

In assembling the deflector with the bowl, the deflector is first clipped over the rim 23 of the bowl in a horizontal position indicated by the dot-and-dash outline 101 in Fig. 1, and is then swung into the vertical position 102, from which it is pushed down, alongside of the inner wall 12 of the bowl, into its operating position 10.

In operation, as the beater 13 revolves around the central vertical axis of the bowl 12, in a clockwise direction, it rotates in a counter-clockwise direction at greater speed around its own axis, and produces a wash in the batch which would continue to travel along the inside wall 12 of the bowl, were it not that the wash encounters the deflector and derives therefrom a centripetal moment of force which overcomes the moment of centrifugal force induced by the rotation and/or revolution of the beater, and thus the heavier liquid particles of the mix are directed into the path of the beater, where they are converted into the desired foam structure, uniformly and rapidly.

Should it be found that, when using large bowls and different kinds of mixture, one deflector would not be sufficient to keep the path of the batch under proper control, additional deflectors can be readily placed at suitable points; as for example at the place indicated by the dot-and-dash position 103 in Fig. 1.

Whatever the position of any such deflector, it can be readily shifted to a different adjustive position upon the rim, or changed to another bowl, when a separately formed deflector is used, as illustrated.

While the separately formed deflector is considered preferable, it is not intended to exclude from the province of the present invention the employment of a deflector element of equivalent form and deflecting action integral with the wall of the bowl, or as a permanent fixture thereon.

So also, the deflector element, of any suitable shape and material, may be mounted on the overhead support which carries the beater and, under favorable conditions, may be caused to move in an orbit suitably related to that of the beater.

The beater 13 is illustrated as a whipping device which may be desirably fabricated of wire, and may be of any desired form, as for example, one of the same general type disclosed in the above-mentioned De Huff application for Letters Patent. The invention has been found, in practice, to yield greatly increased efficiency in the op-

eration of a vertical mixer equipped with such a whipper.

These deflectors can be used, in general, in connection with a bowl of any size, but such a deflector is of particular advantage when used in a bowl of relatively large size having, say a capacity of from 120 quarts and upward.

In a bowl of very large size, say of 340 quart capacity, the use of two such deflectors has been found advantageous and it is possible that more than two could be used to advantage.

The deflector has been found to aid in the incorporation, into a foam structure, of flour and other dry ingredients, if such be used, for the deflecting action seems to help in the assimilation of the dry contents, since it apparently gives direction to the batch, even after the batch is very nearly or completely finished.

This is, of course, very important, particularly when making such batches as those designed for angel food cake and sponge cake, in which it is imperative that the smallest possible amount of agitation shall be used to incorporate the final flour, for too much agitation will toughen the finished cake and affect its commercial value.

From the foregoing disclosure it will be observed that the deflector means, being generally wedge-shaped, increasing in width from bottom to top, has a face disposed at an angle to the inner bowl wall, extending to an edge removed from said wall toward the upright axis of rotation of the beater, and presents a broad deflecting surface protruding toward the beater's periphery at the upper levels of the mix.

Accordingly, the deflector acts for a substantial portion of its length to deflect liquid particles of the mix tending to swirl outside the path of the beater under the action of centrifugal force, so that said particles will be thereby returned into the beater somewhat near the top of the beater, whereby said particles are then impelled downward to the bottom of the bowl, thus imparting to the liquid being broken up a circulating motion having a vertical component, such directional effect causing a combination of the centrifugal motion of the batch with the action of the beater upon said re-directed portion of the batch for the purpose of developing the liquid rapidly into a foam structure.

What is claimed is:

1. A batch-mixing machine of the type which includes a bowl adapted to receive the ingredients of the mix, at least one of which is substantially liquid; a beater device having a support from which it is extended into said bowl through the upper surface of the mix, said beater working through the body of the mix at substantially all levels; and means to impart to said beater a rotary movement around its own axis, and a movement of translation in an orbit circumadjacent to, but spaced from, the inner wall of the bowl; said machine comprising, in combination with said bowl and beater, a deflector means supported in position to intervene between the orbit of the beater and the inner circumference of the bowl, said deflector being generally wedge-shaped, increasing in width from bottom to top, having at least one face disposed at an angle to the inner bowl wall and extending to an edge removed from said wall toward the upright axis of rotation of the beater, so that the deflector presents a broad deflecting surface protruding toward the beater's periphery at the upper levels of the mix, acting for a substantial portion of its length to deflect particles of the mix tending to swirl outside the bowl.

path of the beater under the influence of centrifugal force, and thus said particles will be thereby returned into the path of the beater, whereby said particles are then impelled downward to the bottom of the bowl, thus imparting to the liquid being broken up a circulating motion having a vertical component, such directional effect causing a combination of the centrifugal motion of the batch with the action of the beater upon said redirected portions of the batch for the purpose of developing the liquid rapidly into a foam structure.

2. As a new article of manufacture, a deflecting means for a mixing bowl, comprising an element adapted to intervene between an inner side wall of

the bowl and a beater operating therein, and to be engaged with a circumferential beater-induced flow of ingredients, said element being wedge-shaped, decreasing in width from top to bottom and extending below the upper surface of the batch to be treated, acting to deflect said flow into the path of the beater, while permitting orbital movement of the beater, so that said element causes the normal moment of centrifugal force derived from said orbital movement of the beater to be combined with the action of said beater upon the redirected portions of the batch to impart a substantially vertical flow of the batch downward through the beater for the purpose of developing the liquid rapidly into foam structure.
